UNITED STATES PATENT OFFICE.

JESSE D. PADGITT, OF DALLAS, TEXAS.

STIRRUP-LEATHER STAY.

SPECIFICATION forming part of Letters Patent No. 425,184, dated April 8, 1890.

Application filed October 7, 1889. Serial No. 326,291. (No model.)

To all whom it may concern:

Be it known that I, JESSE D. PADGITT, of Dallas, in the county of Dallas and State of Texas, have invented a new and useful Improvement in Stirrup-Leather Stays, of which the following is a specification.

The object of the invention is to provide a stay which will cause the stirrup to hang in proper position for insertion of the rider's foot in mounting; and the invention consists in the construction and combination of parts, as will be hereinafter fully described and claimed.

In the accompanying drawings, Figure 1 is a side view, Fig. 2 is a horizontal section, and Fig. 3 is a detail perspective side view, of my invention.

A represents a stirrup leather or strap, and B the stirrup; and D is my improved stay, preferably formed by casting it in a single piece or striking it up from a piece of sheet metal, or it may be made of leather or other material. The stay is U shape in cross-section and of a length to embrace the cross-piece b of the stirrup. Centrally of upper edges of the stay D are two outwardly-projecting loops d d, through which the stirrup leather or strap A passes after passing around the outer side of the stay.

The stay D is about the same length as the cross-piece b of the stirrup, and the loops d d are just wide enough for the stirrup leather or strap, and therefore the cross-piece b cannot slide back and forth in the stirrup-leather loop and cause the stirrup to hang at an incline or one-sided.

The stirrup-leather will always be held in the center of the stirrup, so that the foot-bearing will be equal and riding be made easier. To illustrate more fully, let us take a wooden stirrup which is very wide at its upper end, and unless an equally-wide stirrup leather or strap is used the stirrup will slide in the loop and be caused to hang at an

incline or one-sided instead of straight. If my stay is applied to such a stirrup, the straps or leathers, though much narrower than the cross-piece, will always cause the stirrup to hang properly by reason of the central loops d d, which prevent any sliding movement of the stirrup leathers or straps. Much narrower straps or leathers may therefore be used with such stirrups than heretofore, and at the same time with perfect success. Where a stirrup hangs one-sided, it is very disagreeable for a rider to mount, and, as before stated, the foot-bearings are not central and stable, but shift and cause a strain on the feet to keep the stirrups in proper position. The stays also protect the stirrup-leathers from wear, as the stirrup cross-piece turns in them, while they do not move on the leathers or straps at all.

The loops of the stay can be made to fit any size stirrup-leather desired. The stay will save wear on a broad as well as on a narrow stirrup-leather.

Having thus described my invention, what I claim, and desire to secure by Letters Patent, is—

1. The U-shaped stay D, formed along its upper edges with outwardly-extending loops d d of less length than the stay, substantially as set forth.

2. The combination, with the stirrup, of the U-shaped stay embracing the stirrup cross-piece and extending adjacent to the ends thereof and the central loops d d along the upper edges of the stay, and of less length than the stay, to receive the relatively narrow stirrup-strap A, whereby a narrow stirrup-strap may be successfully used on a stirrup having a wide upper end, substantially as set forth.

JESSE D. PADGITT.
